United States Patent Office

Des. 221,384
Patented Aug. 10, 1971

221,384

DATA PROCESSING CONTROL UNIT

Thomas A. Molyneaux, Waterford Township, Oakland County, Mich., assignor to Emerson Electric Co., St. Louis, Mo.

Filed Mar. 6, 1970, Ser. No. 21,771

Term of patent 14 years

Int. Cl. D14—02

U.S. Cl. D26—5

FIG. 1

FIG. 2

FIG. 3

FIG. 4

FIG. 1 is a perspective view of the data processing control unit of this invention;

FIG. 2 is a front elevational view of the unit;

FIG. 3 is a right side view of the unit; and

FIG. 4 is a top plan view of the unit.

The back of the data processing control unit is conventional.

I claim:

The ornamental design for a data processing control unit, as shown and described.
